ABSTRACT

Aerosol shaving lather incorporating therein a small amount of a water-soluble homopolymer of 4,4-bis(hydroxymethyl)-2-alkenyl-2-oxazoline is disclosed.

5 Claims, No Drawings

AEROSOL SHAVING LATHER CONTAINING AN OXAZOLINE HOMOPOLYMER

BACKGROUND OF THE INVENTION

This invention relates to an improved shaving lather. In a particular aspect this invention relates to aerosol-dispensed shaving lather having improved foam stability.

Aerosol shaving creams consist essentially of a soap solution released from a pressurized can in a foamy state for spreading on the shaver's face with fingers or brush.

The soap is generally a combination of triethanolamine, stearic acid and stripped coconut fatty acid, at a concentration of about 7 percent to 12 percent, with a free fatty acid range of about 1 percent to 3 percent. The ratio of stearic acid to coconut oil fatty acid ranges from 70/30 to 90/10.

Either a fluorinated hydrocarbon or a liquefied petroleum hydrocarbon is used as the propellant. Fluorinated hydrocarbons are usually a blend of dichlorodifluoromethane (Propellant 12) with dichlorofluoroethane (Propellant 114) in a weight ratio of 40/60 or 57/43. They are used at a level of about 6 percent to 10 percent in the formulation. Liquefied petroleum hydrocarbons are usually mol blends of about 87 percent isobutane and 13% propane that are used at a level of 3 percent to 7 percent.

A humectant, to hold moisture on the face and prevent drying out of the lather during the shave, is particularly important in aerosol creams. Also important are foam stabilizers which tend to prevent collapse of the foam during the shaving period.

Products of this type are well known. They are disclosed, e.g. in U.S. Pat. No. 2,655,480 issued to Spitzer et al.

SUMMARY OF THE INVENTION

It is an object of this invention to provide improved shaving lathers.

It is another object of this invention to provide aerosol-dispensed shaving lathers having improved foam stability.

Other objects of this invention will be apparent to those skilled in the art from the disclosure herein.

It is the discovery of this invention that a water-soluble homopolymer of a vinyl oxazoline represented by the formula

where R is hydrogen, methyl or ethyl when incorporated in aerosol-dispersed shaving lathers improves the foam stability and provides a lather having smaller gas bubbles whereby a creamier, smoother shaving lather is obtained.

DETAILED DISCUSSION

The homopolymers useful in the practice of the present invention are known in the art. The monomer can

be conveniently prepared by the method of Purcell, U.S. Pat. No. 3,248,397 which is incorporated herein by reference thereto. The monomer polymerizes readily by standing at room temperature, by heating, or by heating in the presence of a polymerization catalyst, many of which are known.

The amount of polymer used is within from about 0.1 to about 1.0 percent of the soap solution, preferably about 0.2 to about 0.5 percent. Conveniently the polymer is employed as an aqueous solution. The term water-soluble as used herein is not intended to limit the invention to the formation of true solutions. It is also intended to include homopolymers which form colloid solutions and dispersions.

The shaving lathers used in the practice of this invention are those based principally on fatty acid soaps, e.g. alkanolamine, sodium, or potassium soaps of lauric, myristic, palmitic, oleic or stearic acids. Other foaming agents can also be present, e.g. salts of alkyl aryl sulfonates or salts of sulfated alcohol, e.g. sodium lauryl sulfate.

The invention will be better understood with reference to the following examples. It is understood, however, that the examples are intended for illustration only and it is not intended that the invention be limited thereby.

EXAMPLE 1

4,4-Bis(hydroxymethyl)-2-isopropenyl-2-oxazoline, 100 g, was dissolved in 400 g of tetrahydrofuran in the presence of 0.7 g of tert.-butyl peroxy pivalate and 2 g of triethanolamine. The mixture was agitated for twenty hours at 60°C during which time high molecular weight polymer precipitated from solution. It was filtered, washed by extraction with a solution of 80 parts methanol and 20 parts tetrahydrofuran. The polymer was dried at reduced pressure. It had a softening point at 100°-140°C and was water-soluble. The dry polymer was hygroscopic. It absorbed 7-9 percent by wt of water at 50 percent relative humidity; 21-24 percent at 76 percent humidity; and 40-47 percent at 90 percent humidity.

A shaving soap was prepared from the following ingredients:

Stearic Acid	6.32 g
Lauric Acid	1.81
Cetyl Alcohol	1.47
Petroleum Jelly	2.27
Sorbitol	3.86
Triethanolamine	4.07
Potassium Hydroxide	0.181
Water	70

The triethanolamine and potassium hydroxide were dissolved in part of the water. The mixture was heated to 70°C and the other ingredients were added with stirring. The mixture was heated until all ingredients had melted and blended and was then cooled and diluted with stirring until all of the water was added. The stearic acid, lauric acid, triethanolamine and potassium hydroxide constitute the soap portion of the above formula. Their combined weight is about 12.38 g of a total of about 90 g, thus constituting about 13.75 percent of the total solution.

An aerosol was prepared from the above soap solution according to the following formula:

3

Soap Solution	90 g
Water containing 0.24 g polymer	10
Freon 12 (dichlorodifluoromethane)	6
Freon 114 (dichlorofluoromethane)	4

The mixture was charged into cans fitted with 20 mm valves, 0.070 stems, and 0.080 bodies. The mixture dispensed foam satisfactorily, the 4,4-bis(hydroxymethyl)-2-isopropenyl-2-oxazoline homopolymer gave a somewhat finer foam, and a noticeably cooler, slightly closer shave with a safety razor.

The foregoing experiment was repeated in all essential details except that polyvinylpyrrolidone (PVP) was substituted for the oxazoline polymer. PVP is commonly used as a foam stabilizer. The aerosol formulated with the oxazoline polymer produced a finer foam and a noticeably cooler, slightly closer shave with a safety razor than did the aerosol formulated with PVP.

EXAMPLE 2

Using the homopolymer of Example 1, an aerosol lather is prepared according to the following formula:

Stearic Acid	7.0%
Coconut Fatty Acid	1.0
Cetyl Alcohol	0.5
Mineral Oil	0.5
Polyoxyethylene sorbitol lanolin	0.5
Arlacel 60 (sorbitan fatty acid ester)	0.5
Tween 60 (polyoxysorbitan fatty acid ester)	4.5
Sorbitol	3.0

The above ingredients are heated to 80°C and there is slowly added with agitation:

Triethanolamine	3.5
Oxazoline homopolymer	.2
Water	78.5

Arlacel 60 is the trademark of Atlas Powder Co. for sorbitan monostearate. Tween 60 is Atlas' trademark for polyoxyethylene 20 sorbitan monostearate.

The mixture is cooled slowly to room temperature with agitation. The stearic acid, coconut fatty acid and triethanolamine constitute the soap portion of the above formula. Their combined proportions constitute about 11.5 percent of the total solution. The soap solution thereby obtained is then charged to a can with propellant as described in Example 1. It produces a rich, creamy, moist stable foam.

EXAMPLE 3

The experiment of Example 2 is repeated in all essential details except the following formula is used:

Stearic Acid	6.0%
Myristic Acid	2.0
Lanolin	0.8
Cetyl Alcohol	0.5
Tween 20 (polyoxyethylene 20 sorbitan monolaurate)	5.0

3,821,116

4

Tween 80 (polyoxyethylene 20 sorbitan monooleate)	5.0%
Triethanolamine	4.0
Borax	0.1

The above ingredients are heated to 80°C and there is added thereto with storage the following mixture pre-heated to 82°:

Neutral sodium stearate	1.0%
Sorbitol	3.5
Oxazoline homopolymer	1.0
Water	71.1

The stearic acid, myristic acid, triethanolamine and neutral sodium stearate constitute the soap portion of the above formula. Their combined proportions constitute about 13 percent of the total solution.

The mixture is packaged as before. It produces a rich, moist lather of excellent stability.

EXAMPLE 4

The experiment of Example 1 is repeated in all essential details except that 4,4-bis(hydroxymethyl)-2-ethenyl-2-oxazoline is substituted for 4,4-bis(hydroxymethyl)-2-isopropenyl-2-oxazoline. A moist, stable foam is obtained.

EXAMPLE 5

The experiment of Example 1 is repeated in all essential details except that 4,4-bis(hydroxymethyl)-2-isobutenyl-2-oxazoline is substituted by 4,4-bis(hydroxymethyl)-2-isopropenyl-2-oxazoline. A moist, stable foam is obtained.

We claim:

1. An aerosol-dispensed shaving lather consisting essentially of an aqueous solution of from about 11.5-13.75 percent soap and from about 0.1 to about 1.0 percent of the homopolymer of an oxazoline corresponding to the formula

50 where R is hydrogen, methyl or ethyl and an effective amount of a propellant.

2. The composition of claim 1 wherein said oxazoline is 4,4-bis(hydroxymethyl)-2-oxazoline.

3. The composition of claim 1 wherein said oxazoline

55 is 4,4-bis(hydroxymethyl)-2-isopropenyl-2-oxazoline.

4. The composition of claim 1 wherein said oxazoline is 4,4-bis(hydroxymethyl)-2-isobutenyl-2-oxazoline.

5. The composition of claim 1 wherein said homopolymer is employed at a concentration within 0.2 to 0.5 percent.
